METHOD AND APPARATUS FOR MANUFACTURING BARBED WIRE

Hans Thiemer, Cologne-Mulheim, Germany, assignor to Felten & Guilleaume Carlswerk Eisen & Stahl A. G., Cologne-Mulheim, Germany

Application May 19, 1937, Serial No. 143,605
In Germany June 16, 1936

10 Claims. (Cl. 140—60)

The present invention relates to a method and means for fabricating twist free barbed wire.

In the usual method of manufacture of barbed wire, two wires are twisted together by the supporting means of the wire storage reels rotating relatively to the supporting means of the winding drum of the finished barbed wire. The clusters of barbs are inserted during the twisting operation or just before the twisting place. 10 The arrangement may be such that the frame carrying the wire storage reels rotates, but also the supporting means of the winding drum may rotate. If it is desired to use this method to produce barbed wire from steel wires, the elasticity of the steel wires is found disturbing and the barbed wire shows a tendency to untwist.

Methods are already known for manufacturing barbed wire from steel wires free of twist. One such method consists in that the clusters of 20 barbs are woven into a steel wire strand previously produced twist free. According to another method, around a steel wire running straight into the barbed wire machine there is wound without twist another steel wire coming from a storage reel supported in the rotary frame and driven with reverse rotation, and the clusters of barbs are inserted just before or in the stranding position. A still further method 25 consists in that barbed steel wire, produced in a known manner with a twist, is overtwisted on the way to the winding drum by means of guiding members, which rotate in the direction of stranding but at increased speed, and the resulting tendency to untwist is allowed to take effect on the further progress up to the winding drum.

According to the present invention, the method and apparatus for fabricating twist free barbed steel wire are based on an entirely different idea. In carrying out the invention there is imparted to each of the wires, from which the barbed wire strand is formed, a rotary movement in the same direction and to such an extent that each of the wires is stressed beyond its elasticity limit. After a barb is wound on the 40 wire, both wires are rotated as a unit around the longitudinal axis of the strand in the same direction as the rotary movement imparted to the individual wires and at a speed equal to the rotary movement imparted to the individual wires. The barbed wire thus made may be wound in ring form as usual. Since a rotary movement of the same direction and speed has been previously imparted to the individual wires, the strand winding takes place without changing 45 the direction and rotary speed of the rotating

movement and the strand is therefore free of twist.

The apparatus for carrying out the method differs essentially from the known barbed wire machines by providing a twisting device between each supply reel and the barb winding means for the purpose of imparting a rotary movement to the individual wires. This twisting device may also be regarded as a distorting device because the individual wires are stressed beyond 10 the elastic limits thereof.

The apparatus for carrying out the method is illustrated in the accompanying drawings.

In the drawings:

Fig. 1 is a plan view of a barbed wire machine 15 according to the invention.

Fig. 2 is a sectional view taken on the line II—II of Fig. 1.

Fig. 3 illustrates a part of the device for feeding the barbed material as seen from the left side 20 of Fig. 1.

Fig. 4 is a sectional view of the device for winding the barbed material as seen from above.

Referring to Figs. 1 and 2, there is mounted on the bed plate 1 of the machine a main driving 25 shaft 2 which is driven by means of a pulley 3 and a belt 4. The rotating and twisting devices 5 and 6 which are coupled together by gear wheels 7, 8 and 9 are driven from the main shaft 2 by means of gear wheels 10 and 11. The twisting devices 5 and 6 are mounted on hollow shafts 12 and 13 and these twisting devices are provided with rollers 14 and 15. The wires 18 and 19 taken from the stationary rotatable reels 16 and 17 are guided through the hollow shafts 12 and 13 and are wound several times round the rollers 14 and 15 so that the wires 18 and 19 are gripped by the rollers 14 and 15 and are twisted when the devices 5 and 6 rotate.

An auxiliary shaft 22 is coupled with the main shaft 2 of the machine through the gear wheels 20 and 21. A crank disc 23 is secured to the auxiliary shaft which by means of the crank 24 actuates the swinging lever 25 so as to actuate a pawl 26 and turn the ratchet wheel 27 and a shaft 28 forwards intermittently during each revolution of the auxiliary shaft 22. The shaft 28 is in this way intermittently rotated so as to provide driving means for feeding the barb forming material.

The barb material 29 and 30 is stored on reels 31 and 32 and passes therefrom over the grooved rolls 33 and 34 which feed the barb material forward. The wires 29 and 30 thereafter pass through guide blocks 35 and 36 which introduce 55

the barb material between the wires 18 and 19 before they meet to be twisted together. The upper roll secured on the shaft 28 of the pair of rolls 33 is coupled with the lower roll by means of gear wheels 37 as shown in Fig. 3. The guide blocks 35 and 36 are provided with passages 38 through which the barb material 29 and 30 is introduced between the wires 18 and 19. While the pair of rolls 33 are driven directly by the shaft 28 as described the pair of rolls 34 are coupled with the shaft 28 through the shaft 39, gear wheels 40 and 41, auxiliary shaft 42 and gear wheels 43 and 44.

The device for winding the barbs consists of a hollow cylinder 46 mounted in the bearing block 45 and fitted at its end with winding fingers 47. A stationary tongue 48 holds the wires 18 and 19 apart just prior to the twisting place and this tongue projects into the hollow space of the cylinder 46 as shown in Fig. 4. A crank disc 50 mounted on the auxiliary shaft 22 actuates a swinging lever 52 by means of the crank 51 and a toothed segment 53 of the lever 52 engages teeth 49 on the cylinder 46 so as to drive the barb winding means. The arrangement is made such that the cylinder 46 carrying the winding fingers 47 is actuated at the moment when the barb material 29 and 30 has been pushed by means of the pairs of rolls 33 and 34 through the bores 38 of the guide blocks 35 and 36 and between the wires 18 and 19 to such a distance that it can be engaged by the fingers 47 of the hollow cylinder 46.

The device for cutting the barb material 29 and 30 includes a rotatably mounted carrier having cutters 55 and 56 and an angular lever 57. Another auxiliary shaft 58 is provided for driving the barb cutting device which is coupled with the main shaft 2 by means of gear wheels 59 and 60. The other end of the shaft 58 carries a crank disc 61 which by means of a crank 62 actuates the lever 57 of the barb cutting device. When the cutters 55 and 56 move upwards their cutting edges slide along the surfaces 63 and 64 of the guide blocks 35 and 36 and thereby sever the barb material projecting out of the passages 38. The arrangement is such that the cutters 55 and 56 are moved upwards on the surfaces 63 and 64 of the guiding blocks 35 and 36 each time the barb material has been wound round the wires 18 and 19 by means of the finger 47 of the barb winding device.

A winding drum 65 for receiving the finished barb strand is mounted in a rotatable frame 66. This frame is coupled with the main shaft 2 by means of gear wheels 67 and 68 and is driven in the same direction and at substantially the same speed as that imparted to the wires 18 and 19 by the twisting devices 5 and 6. The drum 65 is driven by means of a belt 69 which rotates the pulley 70 mounted on an auxiliary shaft 71 arranged in the hollow shaft of the gear wheel 68. The auxiliary shaft 71 is coupled to the drum 65 by means of gear wheels 72 and 73.

Since the wires 18 and 19 slip somewhat on the rollers 14 and 15 of the twisting devices 5 and 6 these devices must be driven at a somewhat greater speed than the frame 66 of the winding drum for receiving the finished barb wire so that the finished barb wire will actually have the same speed as the individual wires 18 and 19.

Although the apparatus has been described for carrying out a method of fabricating barbed wire it will be appreciated that the invention is ap-

plicable to the manufacture of other types of composite wire wherein two or more wires are wrapped around each other, and such applications of the invention may be practiced without departing from the spirit and scope of the invention as set forth in the appended claims.

What I claim is:

1. A method of fabricating barbed wire which comprises, arranging a wire extending from each of at least two sources of supply adjacent each other at a point spaced away from the wire supply, imparting a turning movement to each wire so that each wire is rotated around its longitudinal axis prior to the confluence of the wires whereby each of the wires are wrapped around each other, winding a barb on the wires, thereafter turning the two wires around the axis of the strand in the direction of the turning movement imparted to the individual wires, and winding the strand in a continuous circular form. 15 20

2. A method of fabricating barbed wire which comprises, arranging a wire extending from each of at least two sources of supply adjacent each other at a point positioned away from the supply, imparting a similar twisting movement to each wire so that each wire is rotated in the same direction around its longitudinal axis prior to the confluence of the wires whereby such twisting movement of each wire causes the wires to be wrapped around each other, winding a barb 30 around the wires, thereafter turning the two wires around the axis of the strand in the same direction as the twisting movement imparted to the individual wires, and winding the strand in reel form. 35

3. A method of fabricating barbed wire which comprises, arranging a wire extending from each of at least two sources of supply adjacent each other at a point positioned away from the supply, imparting a similar twisting movement to each wire so that each wire is rotated in the same direction around its longitudinal axis prior to the confluence of the wires whereby such twisting movement of each wire causes the wires to be wrapped around each other, winding a 45 barb around the wires, thereafter rotating the two wires as a unit around the longitudinal axis of the strand in the same direction as the twisting movement imparted to the individual wires and at the same speed of rotation, and winding 50 the strand in a continuous circular form. 40

4. A method of fabricating barbed wire which comprises, arranging a wire extending from each of at least two sources of supply adjacent each other at a point spaced away from the supply, 55 rotating each wire around its longitudinal axis in the same direction and to such an extent as to strain each wire beyond its elastic limit prior to the confluence of the wires so that the longitudinally adjacent parts of the wires are wrapped around each other, winding a barb on the wires, thereafter rotating the two wires around the longitudinal axis of the strand in the same direction as the turning movement imparted to the individual wires and at a speed substantially 65 equal to that of the turning movement imparted to each individual wire, and thereafter winding the strand in continuous circular form. 60

5. A method of fabricating barbed wire which comprises, arranging a plurality of steel wires 70 each extending from a separate source of supply adjacent each other, rotating the supply end of each wire around its longitudinal axis in the same direction and to such an extent as to strain each wire beyond its elastic limit, winding a 75

barb on the wires, rotating all of the steel wires bodily around the longitudinal axis of all the wires, said second mentioned rotation being in the same direction as the turning movement 5 imparted to the individual steel wires and at a speed substantially equal to that of the turning movement of each individual wire, and winding the wires in circular form simultaneously with the rotation of the longitudinal axis of the wires.

10 6. A method of fabricating a stranded cable which comprises, arranging the wires extending from a plurality of individual sources of supply adjacent each other at a point spaced away from each supply, imparting a similar rotating movement to each wire so that each wire is rotated in the same direction around its longitudinal axis prior to the confluence of the wires, and thereafter rotating all the wires as a unit around the common longitudinal axis of the wires at a speed 15 of rotation substantially equal to that of the individual turning movements, and winding the wires in convolution form.

7. Apparatus for fabricating stranded wire comprising in combination, a plurality of wire storage reels, means for guiding the wire extending from each of said reels to a position adjacent each other, means for individually turning the supply end of each of said wires around the longitudinal axis of each wire, means for rotating the 20 wires around the common longitudinal axis of the wires in the same direction of rotation as that of said first mentioned rotating means, and means for winding the stranded wire in reel form.

30 8. Apparatus for fabricating barbed wire comprising in combination, at least two axially stationary rotatable reels each having a supply of wire thereon, guiding means for moving a wire extending from each reel to a position adjacent each other, means associated with each of said 35 40 wires for twisting each wire around its longitudi-

nal axis prior to the confluence of the wires so that the wires are caused to be wrapped around each other, means for winding a barb on said wires, a rotating drum for winding the stranded wire formed by said twisting means, and means for simultaneously turning the strand around the longitudinal axis thereof and in the same direction as that of the twisting movement imparted to each individual wire.

5 9. Apparatus for fabricating barbed wire comprising in combination, two reels each having a supply of wire thereon, guiding means for moving a wire extending from each reel to a position adjacent each other, barbing means arranged adjacent the confluence of the wires for winding 10 15 barbs on the wire and cutting the same, distorting means associated with each of said wires at a point intermediate of said barbing device and the respective storage reel, each of said distorting devices being adapted to turn each wire around its longitudinal axis, a rotating drum for winding the wires, and means for rotating the wires around the common longitudinal axis thereof and in the same direction as that of the rotating movement imparted to each individual wire. 20 25

10 10. A method of fabricating a stranded cable which comprises, arranging the wires extending from a plurality of individual sources of supply adjacent each other at a point spaced away from each supply, rotating each wire around its longitudinal axis in the same direction and to such an extent as to strain each wire beyond its elastic limit prior to the confluence of the wires, and thereafter rotating all the wires as a unit around the common longitudinal axis of the wires at a speed of rotation substantially equal to that of the individual turning movements, and winding the wires in convolution form. 30 35
